(57) **CLAIM**

The ornamental design for a hair detoxification bag, as shown and described.

DESCRIPTION

FIG. 1 is a front perspective view of a hair detoxification bag showing my new design, shown in an environment of use; FIG. 2 is a right side view thereof;

FIG. 3 is a left side view thereof;

FIG. 4 is a rear perspective view thereof;

FIG. 5 is a top perspective view thereof;

FIG. 6 is a bottom perspective view thereof;

FIG. 7 is a left perspective view thereof, shown in a position of use;

FIG. 8 is a front, right perspective view thereof; and,

FIG. 9 is a rear view thereof.

The broken lines showing a mannequin illustrate environmental subject matter only and form no part of the claimed design.

1 Claim, 9 Drawing Sheets
